UNITED STATES PATENT OFFICE

FRED BRANDT, OF TAGUS, NORTH DAKOTA

FUEL HEATING DEVICE

Application filed November 26, 1929. Serial No. 409,936.

The present invention relates to internal combustion engines, and particularly to improvements in feeding fuel thereto.

An object of the invention is to provide improved means for heating air before it enters a carburetor.

Another object is to provide improved means for heating the fuel charge before it enters the carburetor.

Another object is to provide mechanism for the automatic control of the heating devices for the fuel charge.

A still further object is to provide improved devices permitting the fuel to enter the carburetor in liquid form.

Other objects and advantages of the invention will appear from the following description, taken in connection with the accompanying drawings, which illustrate, by way of example, a preferred embodiment of the invention, and in which:

Fig. 1 is a side elevation of mechanism embodying the present invention, and shown for purposes of illustration as being applicable to a four-cylinder internal combustion engine of the tractor type, though it will be understood that the invention, as defined by the appended claims, is not limited thereto;

Fig. 2 is a top plan view, partly in section, of the mechanism shown in Fig. 1;

Fig. 3 is a vertical sectional view of a modified form of air passage to the carburetor;

Fig. 4 is a horizontal sectional view through the structure of Fig. 3 taken on the line 4-4 of Fig. 3.

Referring in detail to the accompanying drawings, the reference numeral 11 indicates the exhaust manifold of an internal combustion engine having an outer end opening 12, through which the exhaust gases pass, and which said gases may reach through either of two passages, namely from the horizontal passage 11 through the downwardly extending passage 13, or from the horizontal passage 11 down through the vertical passage 14 to the lower horizontally extending passage 15 and thence to the end opening 12 of the exhaust manifold. A control valve 50 within the passage 14 deflects the exhaust

gases through either one or the other of the passages just described.

Air reaches the carburetor 18 through an air passage 19 from an air cleaner (not shown). A valve 21 provided with a rod 22 for manual control is located within the air passage 19.

Referring particularly to Fig. 2, when the valve 21 is open, air is permitted to travel through the conduit 19 directly to the carburetor 18; when the valve 21 is closed, the air on its way to the carburetor is diverted through a by-pass 24 into a conduit 25, which passes horizontally through the vertically extending branch 13 of the exhaust manifold.

The conduit 25 opens into an air chamber 27 located between the vertical exhaust passages 13 and 14. Within the air chamber 27

is located a baffle plate 29 slightly curved and extending for the full depth of the air chamber from the lower right-hand corner

thereof towards the upper left-hand corner, as viewed in Fig. 1. The air chamber 27 has its bottom and end walls formed by the exhaust conduits of the motor, as shown in

Fig. 1, and when air is deflected by valve 21 through the by-pass 24, it is heated in the conduit 25 by the gases in the exhaust passage 13, after which it enters the air chamber 27, where it is deflected by the baffle 29,

around the outside walls of the air chamber, three of which are composed of cast iron manifolds, which cause the air to be further heated.

From the air chamber 27, the air is delivered through a conduit 30 again into the conduit 19 at a point beyond the valve 21,

and from this point is delivered to the carburetor 18.

Referring to Figs. 3 and 4, a modified form of air passage to the carburetor is shown which causes the air to be heated to a higher temperature than in the structure just described.

In this modified form, the conduit 25 after passing through the vertical exhaust passage 13 as before opens into an air chamber 27', through the lower part of which passes the horizontal exhaust conduit 15. The chamber 27' extends below and around this conduit, and

is provided with a baffle plate 29' extending diagonally across the chamber in a vertical plane. The end vertical edges of the baffle are in contact with opposite corners of the chamber, as shown in Fig. 4. The upper and lower edges of the baffle are in contact with the top of the chamber and the top of the exhaust conduit 15, as shown in Fig. 3.

In this construction the air enters chamber 27' from conduit 25 and is deflected toward the left of chamber 27', as viewed in Fig. 3, by baffle 29'. The air passes downward on the left side of said chamber to the bottom thereof, thence under the exhaust conduit 15, thence up the right side of said chamber on the other side of the baffle plate, and thence out of the chamber 27' through conduit 30. From the conduit 30 the air passes to the carburetor as already described.

This construction causes increased heating of the air delivered to the carburetor not only by bringing it into heating relation with the two exhaust passages 13 and 14 and the top of exhaust passage 15, but in addition also causes the air to pass completely around the lower horizontal exhaust passage 15, thereby increasing the length of the air heating path and taking additional advantage of the heating ability of passage 15.

The invention provides improved means for preheating the fuel delivered to the carburetor, and, in accordance with the present invention, the mechanism thereof is so constructed as to permit such controlled preheating of the fuel that it is possible, after the motor has been started, to switch from a highly volatile fuel to a heavy fuel of low volatility.

For this purpose, in accordance with the present embodiment of the invention, a circulating liquid system is provided through which liquid flows from a tank 39 down through an outlet pipe 40 to a horizontally extending conduit 41. The conduit 41 enters the cast iron side of the exhaust passage 13 and extends horizontally therethrough and also through the lower horizontal exhaust passage 15, thus subjecting the liquid in said conduit to the heat of the exhaust gases, by which the liquid is heated up to or nearly to the boiling point. At its other end the conduit 41 passes through the vertical end wall of the downwardly extending exhaust passage 14, as shown in Fig. 2. A very small portion of the liquid passing through the conduit 41 is delivered to the carburetor 18 through a pipe 42, the remainder returning to the tank 39 through passage 43, one end of which opens into the vertical conduit 44, and the other end of which opens into the upper portion of the liquid tank 39. Any suitable form of temperature-indicating device may be associated with the liquid conduit 44 through a connection 46.

In the present instance the liquid may be

water, and the tank 39 may be a water tank, though it will be understood that other liquids, particularly those having a higher boiling point than water, may be used.

Adjacent the water tank 39 may be located a fuel tank 48, which, in accordance with the present invention, may contain a relatively heavy fuel oil, and adjacent the tank 48 may be located a second fuel tank 49, which may contain a relatively highly volatile starting fuel, such as gasoline. From each of the tanks 48 and 49 a valve controlled outlet leads to the fuel feed conduit 50, which, in the present instance, extends downwardly from said tanks and delivers one or the other of the two fuels to a horizontally extending heating tube 52, which passes centrally through the conduit 41 and has an increased diameter substantially throughout that part of its length which lies within the conduit 41. This enlarged portion 53 of the feed pipe causes a decrease in the speed of travel of the fuel within the conduit or water jacket 41 for the purpose of giving the fuel a longer time to be subjected to the higher temperature of the water. The feed line is continued from the enlarged portion 53 through the water conduit 44, through the wall of which the feed line 56 delivers the fuel to the carburetor 18.

The foregoing mechanism insures sufficient preheating of a heavy fuel to permit of its being sufficiently atomized to operate the internal combustion engine. As soon as the engine is operated long enough on the volatile fuel, such as gasoline, to heat the water in the tube 41 to the necessary temperature, the heavy fuel, such as fuel oil, may be fed to the carburetor from the tank 48 and the supply of gasoline or other volatile fuel cut off from the tank 49. It will be seen that the foregoing construction has the advantage of permitting the heating medium to reach a sufficiently high temperature to permit the use of a heavy fuel without permitting the temperature of such fuel to be raised too high; at the same time the heating water will not be cooled as it would be were it taken from the cooling system of the motor. Although the heating water, by the present invention, may be heated up the boiling point, it has no effect on the operating temperature of the motor. An important advantage is that the fuel cannot be transformed into a vapor before it reaches the carburetor, as would be the case were the feed line passed through the exhaust passage without the water jacket. Although the enlarged portion 53 of the fuel line is relatively short in length, it is at the same time relatively large in diameter, which permits the flow of fuel to the carburetor to slow down long enough to raise the fuel to the temperature of the surrounding water. Moreover, by the foregoing construction the fuel pipes

are not subjected directly to the heat of the exhaust gases, and therefore cannot be burned or corroded or become fouled.

Various changes may be made in the detailed construction above described by way of illustration without departing from the invention as defined by the following claims.

What is claimed is:

1. Fuel feeding apparatus for an internal combustion engine including an exhaust conduit for said engine, a liquid circulating system having a heating portion located within said exhaust conduit, and a fuel line part of which passes through said heating portion.
2. Fuel feeding apparatus for an internal combustion engine including an exhaust conduit for said engine, a liquid-circulating fuel-heating system having a fuel-heating portion located within said exhaust conduit, the remainder of said system being out of thermal relation to said engine, and a fuel line part of which passes through said fuel-heating portion.
3. Fuel feeding apparatus for an internal combustion engine including an exhaust conduit for said engine, a liquid-circulating fuel-heating system having a fuel-heating portion located within said exhaust conduit, and a fuel line having an enlarged section located within said fuel-heating portion.
4. Fuel feeding apparatus for an internal combustion engine including a carburetor, an exhaust conduit from said engine, an air inlet pipe to said carburetor having a by-pass through said exhaust conduit, a liquid-circulating system having a heating portion located within said exhaust conduit, a liquid delivery line from said system to said carburetor, and a fuel line part of which passes through said heating portion.

In testimony whereof I affix my signature.
FRED BRANDT.
